PATTERN GRADING MACHINE

Shirley Burton, Leicester, England, assignor to
 United Shoe Machinery Corporation, Flemington, N. J., a corporation of New Jersey

Application September 17, 1947, Serial No. 774,531
 In Great Britain October 10, 1946

2 Claims. (Cl. 33—23)

1

This invention relates to pattern-grading machines, and more especially to those of the type disclosed in United States Letters Patent No. 1,933,672, granted November 7, 1933, on application of Kestell and Burton.

Machines of the type under discussion have compounded pantographic mechanisms capable of being regulated at intermediate stages of cutting a pattern when, for example, it is desired to do "center grading," that is, reproduce one or more selected portions of a model at 1:1 ratio, but all other portions at some other ratio. One problem incidental to changing the grading ratio at an intermediate stage of cutting a pattern is to prevent displacing the work with respect to the cutting tool, since a displacement can, and in many cases does, produce a defect in the pattern.

Therefore, the purpose of the present invention is to provide a pattern-grading machine with means by which both grading slides, one of which is superposed upon the other, may be temporarily fixed in location while adjustments of the pantographic mechanisms are being made to vary the grading factors.

In machines of the type under discussion, the location of the cutting tool is fixed, but the tracer or guide pin is carried by a grading slide which is superposed upon another grading slide and normally movable with respect to the latter when the grading ratio is other than 1:1. The two grading slides derive their motions from pantograph levers the centers (fulcra) of which are laterally adjustable to vary the grading ratio.

For the purposes of the present invention the pantograph levers are connected to the slides, respectively, by novel pivotal connections adapted, when loosened, to absorb the motions of the levers caused by adjusting the pantograph centers. In addition, each grading slide is provided with clamping means by which it may be readily, though temporarily, bound in location wherever it may be at any stage to prevent displacement of the work holder while the pantograph centers are being adjusted. During periods of use, as distinguished from periods of adjusting, the clamping means above mentioned will be left loose to free the grading slides, and at the same time other clamping means will be set up tightly to fix the pivotal connections relatively to their respective slides, and thereby render them effective. The grading slides will then move in response to the demands of the pantograph levers.

Referring to the accompanying drawings,

Fig. 1 is a front elevation of the upper portion

2

of a pattern-grading machine embodying the novel features hereinafter described;

Fig. 2 is a top plan view thereof in which portions of the model-holder are broken away;

Fig. 3 is also a top plan view, on a larger scale, of the grading slides and pantograph levers;

Fig. 4 is a vertical section through elements intersected by line IV—IV in Fig. 3; and

Fig. 5 is a vertical section through elements intersected by line V—V in Fig. 3.

As shown in Fig. 1, a punch 1, a die 9, a primary carriage 21, a model- and work-carriage 25 and a model-holder 47 are organized and identified as in the aforesaid Patent 1,933,672.

15 A fixed frame 10 provides support for the elements mentioned above and for others to be described, and maintains the punch 1 and the die 9 constantly in a fixed locality where the punch is reciprocated vertically at high speed by an electric motor (not shown) to cut a pattern. The carriage 25 is provided with jaws 33 arranged to clamp a blank of pattern-board and move it edge-wise between the punch and the die. For this purpose the carriage 25 is superposed upon the primary carriage 21 and is movable relatively thereto in a horizontal plane. The carriage 21 is constrained to a rectilinear path by a horizontal track 19 on the frame 10. A horizontal track 22 (Fig. 2) on the carriage 21 lies at right-angles 20 to its path of travel and constrains the relative travel of the carriage 25 to a straight path.

The model-holder 47 (Fig. 1) is connected to the carriage 25 by a horizontal hingepin 11, and is provided with many slots, variously located, 25 for the reception of individually adjustable spacers equipped with screws 12 by which a sheet metal template or model 13 may be fastened to the holder 47 and thereby supported in a plane cooperatively related to the follower or guide pin 15. The latter may remain fixed in alignment with the punch 1 or it may move horizontally in response to grading demands when either or both of the pantographic mechanisms, hereinafter described, are set for any grading ratio other than 1:1.

35 The guide pin 15 is mounted in a holder 14 affixed to a grading slide 16. This slide is superposed on another grading slide 17 and is movable relatively thereto in a rectilinear horizontal path 40 parallel with the longitudinal edges of a track-bar 18 by which it is guided. The bar 18 is a part of the carriage 17 which also comprises a track bar 20 that lies parallel with the bar 18. A trolley 23, hereinafter described, is arranged to ride 45 along the bar 20.

3

The grading slide 17 is constrained to horizontal travel in a rectilinear path parallel with the path of the carriage 21. Two track bars 24 (Figs. 2 and 3) for guiding the slide 17 are affixed to the frame 10, and so is a track-bar 26 (Fig. 2) along which a trolley 27 is arranged to ride. This trolley is movable to and fro on its track with the same amplitude of travel as the carriage 21, with which it is connected by a rod 28 and other connecting parts. The trolley 23, on the other hand, is movable to and fro along its track 20 with the same amplitude of travel as that of carriage 25 along the tracks 22. To maintain an operative connection of the trolley 23 with the carriage 25 despite relative sidewise travel of the latter, a grooved horizontal bar 30 is affixed to the carriage, while an arm 31 is rigidly related to the trolley and is provided with rollers 32 fitted to and located in the groove of the bar. The arm 31, the trolley 23, and rods 34, 35 are organized to form a movable unit for pantographic purposes.

One pantographic mechanism is arranged to communicate frontward and backward travel of the trolley 23 to the grading slide 16, while another such mechanism is arranged to communicate sidewise travel of the trolley 27 to the grading slide 17. The mechanism for actuating the slide 16 comprises a pantograph lever 36 that derives its operative movements from the trolley 23 with which it is connected by a pivoted sleeve 37. A pivot member 38 carried by the slide 16 engages the lever 36 (Fig. 5) and provides an operating connection. A groove extending lengthwise in the lever 36 is occupied by a fulcrum member 39 (Fig. 4) carried by an adjustable bar 40 and connected thereto by a pivot 41. This pivot constitutes a pantographic center and is adjustable sidewise to and from alinement with the pivot member 38. For this purpose the bar 40 is situated in a groove in the grading slide 17. This slide also carries adjusting mechanism 42 (Fig. 2) to which the bar 40 is connected.

For manufacturing convenience the pivot member 38 is made of two parts (Fig. 5), one screwed into the other, the outer part including a flat plate 43. When the parts are assembled the plate is embedded in the grading slide 16 which is provided with a groove for its reception and with retaining strips 44 that enable it to be shifted to various positions with respect to both slides 16 and 17. The plate part 43 includes a sleeve 45 that projects through a slot 48 in the slide 16 (Fig. 3) and a corresponding slot in the bar 18 of the slide 17. Under operating conditions the pivot member 38 will be fastened to the slide 16 but movable with respect to the slide 17. To this end the slide 16 is provided with a clamping washer 49 and a nut 50 for setting it tightly against the plate 43.

On the other hand, if, during the process of cutting a pattern, a change is to be made in the grading effect of the pantograph lever 36, it will usually be desirable to prevent displacement of the slide 16 while the pantographic center 41 is being shifted. For this purpose the slide 16 is provided with another clamping means comprising a plate 51, a screw 52 and a nut 53. One margin of the bar 18 (slide 17) lies between confronting portions of the slide 16 and the plate 51 to be clamped by them in consequence of tightening the nut 53. Therefore, in practice, the operator will tighten the nut 53 before loosening the nut 50, and, after adjusting the pantographic center

4

41, he will tighten the nut 50 before loosening the nut 53.

A similar combination of clamping means is provided for the other pantographic mechanism which includes the trolley 27 (Fig. 2), a pantograph lever 54 and an adjusting member 55. The lever 54 is connected to the trolley 27 by a pivoted sleeve 56, to the slide 17 by a pivot member 57 (Fig. 4), and to the frame 10 by a fulcrum member 58 and an adjustable bar 59. The members 58 and 59 are connected by a pivot 60 that constitutes a pantographic center, and this center may be shifted to regulate the pantographic effect of the lever 54. For this purpose the bar 59 is installed in a groove 61 in a component part of the frame 10, and is operatively connected to the member 55 to be adjusted thereby.

The pivot member 57 is made of two parts, one screwed into the other, the outer part including a flat plate 62 and a sleeve 63. When the parts are assembled the plate 62 is seated in the slide 17 and overlapped by retaining strips 64 and a clamping member 65, the sleeve 63 then projecting through a slot 66 in the slide which enables the pivot member to be shifted with respect to the slide for adjusting purposes. Under operating conditions the pivot member 57 will be fastened to the slide 17 but movable with respect to the frame 10. To this end the slide 17 is provided with a screw 67 and a nut 68 for tightening the member 65 against the plate 62.

Although the clamping elements 51, 52 and 53 (Fig. 5) are effective to prevent frontward and backward displacement of the guide pin 15 they are not effective to prevent sidewise displacement thereof. Therefore, to prevent displacement of the latter kind, the slide 17 (Fig. 4) is provided with clamping means comprising a screw 69 and a nut 70, the screw having a head 71 with which a sleeve 72 cooperates to clamp a margin of the rear track bar 24 which is a component part of the frame 10 and one of the two fixed bars on which the slide 17 rides when the machine is in operation.

When a change is to be made in the grading effect of the lever 54, by adjusting the pantographic center 60, during the procedure of cutting a pattern, the operator will tighten the nut 70 before loosening the nut 68. After the change has been made the operator will tighten the nut 68 before loosening the nut 70. Since the effect of the nut 70 is to bind the slide 17 to the fixed frame 10, and the effect of the nut 53 (Fig. 5) is to bind the slide 16 to the slide 17, no displacement of the guide pin 15 will be caused by adjusting either of the pantographic mechanisms while these nuts are set up tightly.

Having described my invention, what I claim as new and desire to secure by Letters Patent of the United States is:

1. In a pattern-grading machine of the type in which one pantograph lever is connected to a fixed frame by means including a laterally adjustable fulcrum, and otherwise connected to a grading slide slidable on the frame, and in which another pantograph lever is connected to said slide by means including another laterally adjustable fulcrum, and otherwise connected to a grading slide superposed on the first said slide and movable relatively thereto; clamping means arranged to bind the first said slide to said frame at various positions along its path of travel, clamping means arranged to bind said superposed slide to the first said slide at various positions along its path of travel relative to the latter, two

pivot members carried by said slides, respectively, and engaging said levers, respectively, and two clamping means carried by said slides, respectively, for binding said pivot members to their respective slides in various positions of adjustment, said pivot members being adjustable laterally of their respective slides when their respective clamping means are loose.

2. In a pattern-grading machine, a fixed frame, a model and work carriage supported thereby, a model guide, a tool constrained to a fixed station by said frame, two grading slides mounted on the frame one superposed on the other and arranged to support the guide and said other constrained by said frame to a straight path, two pantographic centers one adjustably mounted on said frame, the other adjustably mounted on said other slide, two pivot members carried by said slides, respectively, but individually adjustable rectilinearly

10

15

and relatively to them, two pantographic levers one connecting said pivot member on said superposed slide and said pantographic center on said other slide, and the other connecting said pivot member on said other slide and said pantographic center on said frame, and two clamping means carried by said slides, respectively, for fastening said pivot members in various locations relative to the slides.
